WATCH BAND TRIMMER

Edward R. Day, Dayton, Ohio

Application March 20, 1948, Serial No. 16,132

6 Claims. (Cl. 30—131)

1

This invention relates to a device for shearing the ends of a hollow sheet metal object without causing any collapse of the hollow object. Specifically, the invention concerns a device for trimming the ends of the connecting links of a watchband to trim them to size to fit between the connecting ears of a watch.

It is commonly known that the connecting links on the ends of a metal watchband are made in standard sizes. That is, the width of the connecting links is of standard dimensions. These connecting links are formed with a substantially cylindrical end portion which is adapted to receive a pin that secures the connecting link to a watch between the connecting ears on the watch. The pins are all of standard diameter.

While the dimensions between the connecting ears of watches to which watchbands are fastened are made to standard sizes, and the connecting links in the ends of watchbands are also made to standard sizes to fit the standard sizes between the connecting ears of a watch, yet in the majority of cases a watchband that is selected by a purchaser does not have the correct width of connecting link to fit the purchaser's watch. While the purchaser could select a watchband that did have the correct width of connecting link, yet the one which has the proper width of connecting link usually does not suit the purchaser's taste and therefore it is necessary to cut down the width of the connecting link to fit the watch of the purchaser.

The usual manner of reducing the width of the connecting link is to either file or grind the width of the link to size. This operation is wasteful and time-consuming, and many times can involve a cost equal to the cost of the watchband.

It is therefore the object of this invention to provide a cutting device by which the ends of the connecting link of a watchband can be quickly trimmed with a metal cutting shear.

It is also an object of this invention to provide a metal cutting shear with an anvil adapted to receive the cylindrical connecting portion of a connecting link of a watchband in such a manner that the width of the connecting link can be trimmed to size without causing any collapse of the cylindrical shape of the connecting portion of the connecting link.

It is another object of the invention to provide a metal cutting shear with an anvil adapted to receive hollow sheet metal parts in a manner that the parts can be trimmed across the hollow section without causing collapse of the hollow part.

2

Further objects and advantages will become apparent from the drawings and the following description.

In the drawings:

5 Figure 1 is a perspective elevational view illustrating the manner of using the device of this invention.

Figure 2 is a perspective elevational view of the device of this invention.

10 Figure 3 is a perspective elevational view of a portion of one of the cutting jaws of this invention and the anvil attached thereto.

Figure 4 is a vertical cross-sectional view taken through the anvil and the cutting jaws illustrated in Figure 3.

15 Figure 5 is a cross-sectional view of the anvil body.

Figure 6 is an end elevational view looking at the left end of the anvil body of Figure 5.

20 Figure 7 is an elevational view of the core anvil that is placed within the anvil body.

Figure 8 is an end elevational view looking at the left end of the core anvil of Figure 7.

25 Figure 9 is a perspective elevational view of a modified construction of the device.

Figure 10 is a vertical cross-sectional view of the device illustrated in Figure 9.

Figure 11 is an end elevational view looking at the left-hand end of the device shown in Figure 30 10.

Figure 12 is an elevational view of the core anvil of the device shown in Figure 10.

Figure 13 is an end elevational view of the core anvil of Figure 12.

35 Figure 14 is a cross-sectional view of the adjusting screw of the device of Figure 10.

Figure 15 is an end elevational view of the adjusting screw of Figure 14.

In this invention the device consists of a pair 40 of cutting jaws 10 and 11 that have the shearing faces 12 and 13 respectively and cutting edges 14 and 15 respectively. The jaws 10 and 11 are pivotally connected together by the pivot pin 16. The handles 17 and 18 are connected to the jaws 10 and 11 respectively to operate the jaws.

45 One of the cutting jaws, such as jaw 11, is provided with an anvil body 20 which may be secured to the cutting jaw 11 in any suitable manner, such as welding or brazing, or the body 50 can be cast as an integral part of the jaw 11. This anvil body 20 extends from the cutting jaw in a direction away from the shearing face 13 of the cutting jaw, thus providing no conflict with the cutting jaw 10.

55 However, it will be understood that the anvil

body 20 could be applied to the cutting jaw 10 in place of the cutting jaw 11, if desired.

The anvil body 20 has an opening 21 provided therein, which opening has the terminating end 22 thereof terminating in the plane of the shearing face 13 of the cutting jaw 11. If the anvil body 20 is a piece separate from the cutting jaw 11, as illustrated in the drawing, a recess is provided in the cutting edge 15 of the cutting jaw 11 which forms a part of the opening 21 so that the terminating end 22 of the opening 21 is in the plane of the shearing face 13 of the cutting jaw 11.

The anvil body 20 is provided with a cutaway portion 23. This cutaway portion is arranged substantially along the axis of the opening 21, thus substantially cutting away one-half the anvil body 20 at the forward portion thereof adjacent the cutting edge 15 of the jaw 11. This cutaway portion 23 provides an open section in which a connecting link of a watchband is placed when the ends of the band are to be trimmed.

A core anvil 25 is positioned within the body anvil 20. This core anvil 25 has a threaded portion 26 which threadedly cooperates with the threaded bore 127 in the anvil body 20 to place the core anvil in coaxial alignment with the opening 21. The core anvil 25 also has a reduced diameter portion 27 that is of lesser diameter than the diameter of the opening 21, thereby providing a space between the portion 27 of the core anvil and the surface of the opening 21 in which the sheet metal connecting link of a watchband 30 is received, as shown in Figure 1.

The terminating end 28 of the core anvil 25 terminates in the plane of the shearing face 13 of the cutting jaw 11.

The core anvil 25 is secured in position along the anvil body 20 by means of a set-screw 29.

To provide adjustment to set the terminating end 28 of the core anvil 25 in the plane of the shearing face 13 of the jaw 11, the anvil 25 can be rotated, and when the proper position is obtained the set-screw 29 is forced into engagement with the anvil 25.

The use of the device will be apparent from an inspection of Figure 1 wherein the cylindrical connecting portion 40 of a connecting link 41 has been placed over the reduced diameter portion 27 of the core anvil 25 and lays within the space between the portion 27 and the surface of the opening 21. Since the termination of the opening 21 and of the reduced diameter portion 27 are in the plane of the shearing face 13 of the jaw 11, the end of the connecting link 41 can be trimmed without crushing or deforming the cylindrical portion 40 of the connecting link. After one side of the link 41 is trimmed, the position of it can be reversed and the opposite side trimmed.

In Figures 9 to 15 inclusive there is illustrated a modified arrangement of the device of this invention wherein an adjusting screw is provided to adjust the position of the connecting link of the watchband to accurately control the amount trimmed from each side of the connecting link.

In this device there is provided an anvil body 50 having the core anvil 51. These parts cooperate in the same manner as heretofore described. However, the core anvil 51 is provided with the threaded portion 52 which threadedly engages the threaded portion 53 of the anvil body 50 to hold the core anvil in position, the set screw 54 being provided for locking the core anvil in the anvil body.

The core anvil 51 is also provided with a threaded portion 55 on which there is placed an adjusting screw 56 in threaded engagement therewith. This adjusting screw 56 can be rotated within the recess 57 provided in the anvil body 50 for the same.

By adjusting the screw 56 along the length of the threaded portion 55 of the core anvil 51, the amount of the connecting link that extends beyond the shearing face 13a of the jaw 11a can be controlled. By providing indices 60 along one face of the recess 61 in the anvil body 50, the amount to be trimmed from each or both sides of the connecting link can be accurately determined.

While the forms of the device disclosed and described herein constitute preferred forms of the invention, yet the device is capable of modification without departing from the spirit of the invention, and all modifications that fall within the scope of the appended claims are intended to be included herein.

Having thus fully described my invention, what I claim as new and desire to secure by Letters Patent is:

1. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw, said body having an opening therein in alignment with and normal to the said shearing face of the said jaw and terminating in the plane of the shearing face of the said jaw to receive a hollow sheet metal article, and a core anvil of lesser transverse cross-section than said opening in said body carried by said body and disposed coaxially in said opening with the end thereof terminating in the plane of the shearing face of the said jaw for disposition within a hollow metal article in said opening.

2. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw, said body having an opening therein in alignment with and normal to the said shearing face of the said jaw and terminating in the plane of the shearing face of the said jaw to receive a hollow sheet metal article, a core anvil of lesser transverse cross-section than said opening in said body carried by said body and disposed coaxially in said opening with the end thereof terminating in the plane of the shearing face of the said jaw for disposition within a hollow metal article in said opening, said core anvil being movable in said body axially of said opening for adjustment of the terminating end thereof relative to said shearing face, and locking means between said anvil body and said core anvil.

3. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw, said body having a cutaway portion forming a surface in a plane normal to said shearing face, a recess 75 in said surface to receive a hollow sheet metal

article and having the terminating end thereof in the plane of said shearing face, and a core anvil carried on said anvil body having the surface thereof spaced from the surface of said recess but parallel thereto forming a space therebetween to receive the wall of a hollow sheet metal article.

4. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw and normal thereto, said body having a cutaway portion forming a surface in a plane normal to said shearing face and extending from the cutting edge of said jaw, a recess in said surface to receive a hollow sheet metal article and having one end thereof terminating in said shearing face thereby forming a recess of like contour in the cutting edge of said jaw, a core anvil carried on said body and positioned within said recess and having the surface thereof in spaced relationship with the surface of said recess thereby forming a space therebetween to receive the wall of a hollow article, one end of said core anvil terminating in the plane of said shearing face.

5. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw, said body having an opening therein in alignment

with and normal to the said shearing face of the said jaw and terminating in the plane of the shearing face of the said jaw to receive a hollow sheet metal article, a core anvil of lesser transverse cross-section than said opening in said body carried by said body and disposed coaxially in said opening with the end thereof terminating in the plane of the shearing face of the said jaw for disposition within a hollow metal article in said opening and a gauging device movable relative to said core anvil to regulate the length of a hollow article positioned on said core anvil.

6. A sheet metal cutter for trimming hollow sheet metal parts comprising, a pair of cutting jaws pivoted together in cooperative association and including means for moving the jaws relative to one another, one of said jaws including an anvil body projecting therefrom in a direction away from the shearing face of the said jaw, said body having an opening therein in alignment with and normal to the said shearing face of the said jaw and terminating in the plane of the shearing face of the said jaw to receive a hollow sheet metal article, a core anvil of lesser transverse cross-section than said opening in said body carried by said body and disposed coaxially in said opening with the end thereof terminating in the plane of the shearing face of the said jaw for disposition within a hollow metal article in said opening and a gauging device carried on said core anvil and movable relative to the same to regulate the length of a hollow article positioned on said core anvil.
